CROSSCUT SAW HANDLE

Filed May 31, 1923

FIG. 1.

FIG. 2.

FIG. 3.

Inventor:
Robert C. Gagnon

Patented Jan. 6, 1925.

UNITED STATES PATENT OFFICE.

ROBERT C. GAGNON, OF EAGLE LAKE, MAINE.

CROSSCUT-SAW HANDLE.

Application filed May 31, 1923. Serial No. 642,702.

To all whom it may concern:

Be it known that I, ROBERT C. GAGNON, a citizen of the United States, and resident of Eagle Lake, in the county of Aroostook and State of Maine, have invented a new and useful Crosscut-Saw Handle, of which the following is a specification.

This invention relates to improvements in saw handles, and particularly to a movable saw handle, adapted for use on cross cut saws.

An object of the invention resides in providing a saw handle having means for removably locking the end portion of a saw thereto.

Another object of the invention resides in providing a saw handle structure, where in a handle portion is formed with a hollow sleeve receiving and housing a spring member attached to the tension adjusting means at one end of the handle portion, while the other end is attached to a split bar member, movably mounted in the other end portion of the handle, and having the slot therein arranged in alignment with the slotted end portion of a saw receiving member, said bar member having a locking lever at the end adapted to engage one edge of a saw, for locking it in the saw receiving member to be held therein by the tension of the spring housed within the handle.

The invention also includes other objects and improvements in the details of construction and arrangement of the parts, which are more particularly pointed out in the following description and claims, directed to a preferred form of the invention, it being understood, however, that various changes in the specific construction, and arrangement of these parts may be made, without departing in any way from the spirit and scope of the invention as described and claimed.

In the drawing, forming a part of this application:

Figure 1 is a side elevation of the end portion of the saw equipped with a handle constructed according to this invention.

Figure 2 is a vertical transverse sectional view, through the saw handle, the locking lever being in released position.

Figure 3 is a vertical sectional view, taken at right angles to the section shown in Figure 2, through the saw handle.

The improved handle includes a hollow handle member 1, which is formed with an

enlarged bore 2, opening through one end thereof and communicating with a smaller bore 3, at the outer end of said handle member. The smaller bore 3 receives the cylindrical portion 4 of an adjusting member 5, adapted to adjust the tension of the spring 6, housed within the bore 2, through the screw threaded connection with the threaded rod 7, having connection with one end of the spring 6. It will be seen that the rotation of the adjusting member 5 on the end of the handle will effect an axial movement of the screw threaded rod 7, in order to pull the spring through the bore 2. The opposite end of the handle is provided with a reduced outer diameter for mounting a saw receiving member 8, provided with a slot 9 for receiving one end of the saw 10. The inner end of the slotted portion is provided with a plurality of transverse ridges, as indicated at 11, for engaging the end of the saw, and have a bighting action thereon for effecting the rigid mounting of the handle on the end 80 of the saw against slipping. A slotted bar member 12 has the slot therein arranged in alignment with the slot 9 of the saw receiving member 8, and one end of which is connected with one end of the spring 6, 85 while the other end pivotally mounts the end of a slotted lever 13, provided at 14, with a pin connection between the slotted end portion which is movable in an eccentric relation with the pivot 15 of the lever 90 with the slotted bar member, so that said pin is adapted to engage the opposite end of the saw, from that seating against the toothed portion 11, in order to effect the tensioning of the spring 6, for locking the 95 handle on the saw. The lever 13 is of angular form, as indicated in the drawing, having a handle portion 16, at which point the slotted portion is joined. The angular portion is adapted to fit around the end 100 of the saw 10, in the manner illustrated in Figure 1, so that the pin 14 will pass beyond the line of pull of the spring 6 on the pivot 15, in order that the lever will be held in the position shown in Figure 1. 105 The spring 6 may be tensioned by the setting of an adjusting screw 5 to exert a desired pull on the slotted member 12, in order that the saw 10 will be firmly held in said saw receiving member, while the 110 same is in use.

It will be seen that a readily detachable

or attachable saw handle has been provided, which will be securely held on the end of a saw, during the normal use of the same, through the tension of the spring 6, and 5 the cooperation of the pin 14 and the knife at the roughened edge 11 of the slot 9, in the saw receiving member.

What is claimed is:

1. A saw handle, comprising a hollow 10 handle portion, a saw receiving portion mounted on one end of said handle portion and formed with a slot for receiving a saw, a slotted bar member mounted in the handle portion and saw receiving member also 15 adapted for receiving the end of the saw, a resilient member mounted in the handle portion and connected with the bar member, and an adjustable connection with said resilient member and the other end of the 20 handle, and a rocking lever carried by the outer free end of said bar member adapted for cooperation with the saw receiving member for locking a saw therein.
2. A removable saw handle comprising a 25 handle portion formed with a central bore, a coil spring mounted in said bore, an ad-

justable connection between said coil spring and one end of the handle, a bar member mounted in the bore and connected with the other end of said coil spring, said bar member being formed with a slot extending through the outer end thereof, a coil receiving member mounted on the other end of the handle portion formed with a slotted end for receiving the end of the saw, 30 the slot in said saw receiving member and said bar member being in alignment, and a lever pivoted to the slotted end portion of said bar member, having a pin mounted eccentrically with the pivotal connection of 35 the bar member, for engagement with the edge of the saw, said lever being operable in one position to effect the engagement of said eccentric pin with the edge of a saw, for locking it in the saw receiving member 40 through tensioning the coil spring, and adapted to release the handle from said saw, in another position thereof. 45

ROBERT C. GAGNON.
